UNITED STATES PATENT OFFICE

PAUL L. CROWE, OF BALTIMORE, MARYLAND

COMBINED FUEL BLOWER AND PULVERIZER

Application filed August 24, 1927. Serial No. 215,099.

This invention relates to certain new and useful improvements in a combined fuel blower and pulverizer and has for its particular object the provision of a blower and 5 pulverizer encased in a housing and its parts so assembled as to provide a unitary structure.

A further object of the invention is the provision of a combined fuel blower and pulverizer, including grinder wheels, a sleeve therefor, and motors for the sleeve, and means in said sleeve to constitute a fan when the device is in operation for discharging the pulverized material ground by the grinder 15 wheels.

A further object of this invention is the provision of a combined fuel blower and pulverizer, which will thoroughly and positively pulverize all materials therein into a finely 20 divided state, and a means associated with the pulverizer whereby said materials may be conveyed from the machine.

A still further object of this invention is the provision of a combined blower and pulverizer, including a casing and housing, 25 motors located in the casing, grinders located in the housing, and a blower fan carrying sleeve mounted in the housing and casing and associated with said motors and grinders for 30 the operating of the grinders by virtue of the motors.

A still further object of this invention is the provision of a combined fuel blower and pulverizer having a casing, a sleeve rotatably 35 mounted in the casing and equipped with a fan, a motor mounted in the casing and secured to said sleeve for rotating the latter, and pulverizers located in the casing and having communication with the interior of the 40 sleeve and operated through said sleeve by virtue of said motor.

A still further object of the invention is the provision of a combined blower and pulverizer, that can be easily and quickly 45 assembled, and is of such construction that when assembled the cost of manufacturing and use of space is reduced to a minimum.

With these and other objects in view, the invention consists in certain novel features, 50 combination and arrangement of parts as will

be hereinafter more fully described, pointed out in the accompanying drawings, and claimed.

In the drawings,

Figure 1 is a transverse sectional top plan view, illustrating the complete assembly of 55 my improved combined fuel blower and pulverizer;

Figure 2 is a side elevational view of my 60 improved invention;

Figure 3 is an enlarged detailed sectional view of the pulverizer and the carrying sleeve 65 therefor;

Figure 4 is a vertical sectional view taken on the line 4—4 of Figure 1;

Figure 5 is a side elevational view of the 65 casing;

Figure 6 is a detailed sectional view of the 70 turbine motor;

Figure 7 is a transverse sectional view 70 taken on the line 7—7 of Figure 6;

Figure 8 is a transverse sectional view 75 taken on the line 8—8 of Figure 6; and,

Figure 9 is a side sectional view of the 75 grinder and its associated parts.

The present invention relates to the construction of a combined blower and fuel pulverizer, which includes a combined casing and housing enclosing motors and pulverizer wheels, and a fan carrying sleeve associated 80 with said pulverizer wheels and motors, so that when material is fed to the wheels it will be thoroughly pulverized and forced into the sleeve where it is blown into a furnace by a fan carried thereby, the unitary construction of the assembly reducing the cost of manufacturing, as well as operating costs.

When constructing the device, there is provided a casing 5 having secured to one side face thereof a housing 6, which when assembled provides a complete unit, and located centrally of the housing and casing and journaled transversely therethrough, is a rotatable shaft 7, rotatably mounted in suitable bearings 8, which are supported in any suitable manner to the casing and housing, 5 and 6, respectively. Mounted on this shaft 7 and rotatable therewith, is an annular sleeve 9, and the interior of said sleeve is provided with a plurality of relatively spaced 100

longitudinally extending serpentine blades 10, which blades extend throughout the entire length of said sleeve and constitute a fan for the purpose of creating a draft for blowing material therefrom, when the sleeve is rotated.

A peripheral motor 11 is located in said casing and secured to said sleeve, to rotate the latter when said motor is energized, this motor 10 providing the dual function of rotating the sleeve and causing a forced draft by virtue of the blades carried in the sleeve to blow all materials in said sleeve therefrom. To provide means for allowing material to enter said sleeve, there are formed therein, openings 12, adjacent each end thereof, these openings being in an annular series throughout the entire circumference of said sleeve and are arranged at a relatively spaced distance apart, 15 and the walls of said openings are slightly curved to constitute fan blades 13, which cooperate with the blades 10 in providing sufficient draft through said sleeve to drive material therefrom.

25 One set of openings is located in the housing, the purpose of which will be hereinafter more described, and the other set of openings at the other end thereof, is located adjacent the inner face of the peripheral motor 11, the 30 purpose of which location will be hereinafter more fully described.

To provide an auxiliary means for the operating or the rotating of the sleeve, I place in said casing and secure to said sleeve, a turbine motor 14, and this motor is separated from the peripheral motor 11 by the openings 12, and it is equipped at its outer terminals with the usual buckets 15, which contact with the inner walls of the casing 5 and 40 communicate with a dual fluid passage 16, which passage extends out through the casing 5 to a feed connection 17, which is also provided with dual openings 17', as clearly illustrated in Figure 7 of the drawings.

45 The connection 17 is secured to a supply source and conveys fluid through one of the openings 17' to the buckets 15 for the purpose of rotating the sleeve 9, and excess fluid is permitted to escape from said buckets through 50 the other opening 17', when the same communicates therewith.

To provide a means for allowing outside air to be drawn into the casing 5, I provide the outer wall thereof, with openings 18, and the 55 air passing through said openings passes around the periphery of said peripheral motor 11, in and through the openings 12 in the sleeve 9, and this passage of air will assist in creating additional draft in the sleeve 60 9 and will also provide a cooling means for the motor 11 during the rotation thereof. To provide sufficient air space for the passage of said air about said motor, I secure to the inner wall of the casing 5, a plurality of bearing lugs 19, which are secured to the inner

surface of said casing and radiate inwardly therefrom, and provide a sufficient air pocket to permit said motor to freely rotate and be cooled by the passage of air thereover.

70 Located in the housing 6 and secured to the sleeve 9, is the pulverizer, which consists in its preferred form of a pair of beveled grinding wheels, 20 and 21, respectively, the beveled faces of said wheels being opposed to provide an inlet throat to receive materials fed into the housing by a hopper 22 carried thereon, the hopper being so located that a constant flow of material is assured between the opposing faces of the grinding wheels. The wheel 20 is keyed to the sleeve 9 for rotation therewith, and secured to the inner side face of the outer wall of the housing, is the wheel 21, which is relatively stationary, and that surface of the grinding wheels below the bevels, which constitutes the pulverizing surface, 75 is in close proximity to each other and provides a grinding surface to reduce all materials fed therein, to a finely pulverized state, and if it is desired to increase or decrease the size of the material pulverized, it is only necessary to increase or decrease the width of the grinding wheels, as desired.

80 To assure a means, whereby the materials fed between the bevel faces of the wheels may be conveyed to the interior of the sleeve, I locate the grinding surfaces of said wheels directly over that set of openings 12, which are located in the housing. Thus, it can be readily seen that the materials forced in the throat of the grinding wheels, defined by the beveled surfaces thereof, will be thoroughly pulverized between the grinding surfaces, 85 conveyed into said sleeve, from whence it is 90 conveyed by the created draft therein, to its destination.

95 It is to be understood that while there are shown two grinding wheels, which constitute the pulverizers, that a single wheel can be used, or the wheels can be in series of two, 100 three, or four, and no particular stress is laid 105 on the number of wheels used and their particular construction, as the result is the same, whether it is one wheel or a multiplicity of wheels used.

110 Secured to the outer wall of the housing 6, centrally thereof and concentrically with the sleeve 9, is an outlet member 24, which has a flaring mouth 25, so that all materials in said sleeve may be readily blown therefrom, 115 through said outlet member.

120 When the device is assembled, as described, the hopper 22 is continuously packed with material, and either the peripheral motor 11 is energized, or fluid is forced to the turbine, 125 and whichever motor is used will cause a rotation of the sleeve 9, which rotation will create a draft in said sleeve, and as the material is forced through the grinding surfaces of the pulverizers it is reduced to a finely 130 pulverized state and will drop through the

openings 12 into said sleeve and thence conveyed therefrom through the member 24 to its proper designation by virtue of the fan blades.

5 When the motor 11 is used, air will be drawn through the openings 18, around said motor, by virtue of the bearing lugs 19, and will pass through the openings 12 in the sleeve 9 and mix with the created air there-
10 in, to assist in forcing the material there-
from.

Figure 9 illustrates a slightly modified form of the invention, the construction in the main being identical with the exception of 15 one of the grinding wheels, which is designated by the numeral 26, this wheel being annular in formation and is secured to the inner wall of the housing 6 by the usual fastening means 23, and is so associated with the 20 bevel wheel 20 as to provide a full grinding surface, as in the present invention, this illustration being made to convey that the details of construction of the grinding wheels are not limited to the form shown.

25 It is to be understood that certain minor features and changes may be resorted to without departing from the spirit and scope of the invention as claimed.

Having thus described my invention, what 30 I claim as new is:

1. A combined blower and pulverizer, comprising a casing and a housing, a sleeve rotatably mounted transversely in said housing and casing, a motor located in said casing and 35 secured to said sleeve for rotating the same, a fan located on the interior of said sleeve, grinding wheels located in said housing, one of said grinding wheels secured to and rotatable with said sleeve and communicating therewith, the other of said grinding wheels secured to the housing, and a fan blade carried by the sleeve to constitute a blower.

2. In an apparatus of the class described, a casing and housing, a sleeve transversely 45 mounted for rotation in said housing and casing, fan blades on the interior of said sleeve constituting a blower, a grinding wheel secured to and rotatable with said sleeve, a second grinding wheel secured within the 50 housing adjacent the said first named grinding wheel, said sleeve and its associated grinder having a communication therein, said communicating passage also providing an air passage for atmospheric air, and air 55 openings formed in said casing to permit said air to travel into said sleeve.

3. A combined blower and pulverizer comprising a casing and housing in communication with each other, a hopper secured to said 60 housing, a sleeve transversely rotatable in said housing and casing, a motor located in the casing and secured to the sleeve for rotating the same, grinder wheels located in the housing, said grinder wheels having beveled 65 faces constituting a throat located directly

beneath the hopper, said sleeve carrying one of said grinding wheels and provided with means for establishing a feeding communication between the grinder carried therein, and fan blades carried by the interior of the 70 sleeve constituting a blower when rotated for driving material therefrom.

In testimony whereof he hereunto affixes his signature.
